United States Patent

Des. 236,597
Patented Sept. 2, 1975

236,597

BICYCLE REFLECTOR

Norbert A. Kirk, 6912 N. Ashland,
Chicago, Ill. 60626

Filed Feb. 8, 1974, Ser. No. 440,732

Term of patent 14 years

Int. Cl. D10—06

U.S. Cl. D10—111

FIG. 1

FIG. 2

FIG. 3

FIG. 4

FIG. 5

FIG. 6

FIG. 1 is a perspective view of the bicycle reflector showing my new design;

FIG. 2 is a side elevation thereof, the opposite side being a mirror image;

FIG. 3 is a front elevation thereof;

FIG. 4 is an end elevation thereof;

FIG. 5 is a top view thereof; and

FIG. 6 is a bottom view thereof.

The oblique line shading in FIGS. 1 and 2 indicates a reflective surface.

I claim:

The ornamental design for a bicycle reflector, as shown and described.
